UNITED STATES PATENT OFFICE.

JOSEPH AMON, OF NEW YORK, N. Y.

ELECTRIC-LAMP SOCKET.

No. 856,755.

Specification of Letters Patent.

Patented June 11, 1907.

Application filed March 1, 1906. Serial No. 303,699.

To all whom it may concern:

Be it known that I, JOSEPH AMON, a subject of Austria, residing in the borough of Manhattan, in the city, county, and State of New York, have invented certain Improvements in Electric-Lamp Sockets, of which the following is a specification.

My invention has relation to sockets for electric lamps, and the objects of my invention are: first, to produce a socket which may be easily and quickly installed; second, to secure the contact plates in the socket without screws and to so construct and arrange the contact plates therein that electrical and metallic contact with the conducting wire may be easily and securely made; third, to simplify the form of the several mechanical parts composing the socket referred to in order to effect an economizing of time and labor in the manufacture of the whole appliance; and fourth, to so construct and adapt the insulating support of the socket as to make the socket suitable for general as well as decorative and illuminating purposes.

The invention consists in the improved socket for electric lamps which will be fully described hereinafter and finally pointed out in the claims.

My improved electric lamp-socket is illustrated in the accompanying drawings, in which

Figure 1 represents a vertical section of the lamp-socket with the clamping-plate and screw-nut detached therefrom, Fig. 2 is a vertical section of the same kind of lamp-socket provided with binding-screws and an inclosing-cap or casing, Fig. 3 is a vertical transverse section of the lamp-socket with a switch-mechanism applied thereto, Figs. 4 and 5 are vertical transverse sections taken at right angles to the plane of the section shown in Fig. 3 and showing details of the switch mechanism, Figs. 6, 7 and 8 illustrate different constructions of making electrical connections with the switch mechanism, Fig. 9 represents a section and top-view of the insulating support, Fig. 10 is a plan-view of the base of the support, Fig. 11 is a side-view and top-view of the clamping-plate, and Figs. 12 to 18 are details of the various parts used in my improved lamp-socket.

Similar letters of reference indicate corresponding parts in the different figures of the drawings.

The electric-lamp socket shown in Fig. 1 is composed of the following parts—that is, a support 1 of insulating material, contact plates 2 and 3, a screw 4, a clamping plate 5 60 and the nuts 6 and 7.

The insulating support illustrated in Figs. 9—10 has within a thread 8 adapted to the base of any of the standard lamps; the thread 8 again has a channel 9 to permit the passage of contact spring 2, shown in detail in Fig. 13; extending through the lower portion of the insulating support are perforations 10 10', Fig. 9; the contact plates 2 and 3 are placed in these perforations and are by 70 means of a suitable binding substance securely fastened in the insulating support. The use of a binding substance is not essential to hold contact plates 2 and 3 in place. They may be sufficiently secured in the insulating support by merely inserting the same in the perforations and pressing them against the support. The lower portion of the insulating support has in its center a hole 11 Fig. 9 to receive screw 4 and a square 8c hole 12 for the head of screw 4 the object of which is to prevent a turning of the screw. Screw 4 is permanently fastened in the support and held in place by means of nut 7. To prevent electrical connection of the contact plates 2 and 3 I provide elevation 13 at the outer surface of the base of the insulating support. The lower exterior circumference of the insulating support has a thread 14 Fig. 9, upon which casing 15 Fig. 2 is 90 screwed for the protection of the contact plates; said casing being provided with an interior thread adapted to that purpose.

The electrical connections of the lamp socket represented in Fig. 1 with the conducting wires are produced by simple mechanical pressure by means of clamping plate 5 represented in detail in Fig. 11. This clamping plate is also made of insulating material and has two elevations 16 Figs. 1 and 100 11, each of which is provided with a recess into which the conducting wires are placed when socket is installed. These recesses are of obtuse-angled form to prevent the conductors from falling out or being displaced. 105 In the center clamping plate 5 has a hole 17 to permit the passage of screw bolt 4; by means of nut 6 clamping plate 5 is forced down.

In Fig. 2 the identical kind of socket with 110 the same kind of contact plates as represented in Fig. 1 is shown, except that I em-

ploy binding screws 18 in this form of socket for the purpose of making electrical contact, and for the protection of the contact plates I use a casing 15 interiorly threaded and 5 screwed upon the exterior thread 14 at the lower portion of the insulating support. This form of my socket illustrates how the same may be used for general purposes.

The construction of my socket may be 10 adapted for use in connection with a key or switch mechanism. Figs. 3—4—5 illustrate my socket provided with a switch mechanism. It is evident that the manner of constructing the said mechanism may 15 vary considerably and I do not make any specific claim upon the key shown herein. As clearly shown in Fig. 3 the characteristic elements of the socket herein before described have been entirely retained therein.

20 The socket illustrated in Fig. 3 is composed of the following parts, viz., the insulating support 19 provided for the purpose of receiving the switch mechanism with a chamber 20, and likewise having within a thread 25 8, and an exterior thread 14, the metal contact plates 21 and 22 with the binding screws 18, a key-contact-breaker hereinafter described and a casing 15.

The key-contact-breaker is illustrated in 30 detail in Figs. 16—17—18. Referring thereto 23 is the axle or rod, and 24 the hub-handle attached thereto, 25 the insulating part shown in Fig. 17, the contact part 26 loosely carried thereon; the insulating part 25 is provided at one end with a recess 27 to permit screw 28 to be secured to rod 23. Screw 28 holds the entire switch mechanism in place. The circuit is established and broken by 35 means of contact springs 29 and 29' pressing firmly against the insulating part 25. Contact spring 29 is secured to contact plate 22 by means of rivet 31; said contact plate 22 has a perforation 43 for the passage and support of rod 23; contact spring 29' is secured by means of rivet 31 to contact plate 30, 40 which establishes the electrical connection with the base of the lamp. The adjustment of the switch mechanism described is very simple, the more so as an exact fitting of its 45 50 several parts to one another is not absolutely essential.

In Figs. 6, 7 and 8 are shown different means of making electrical contact of the socket therein shown with the conductors, the same being effected by simple mechanical pressure.

Fig. 6 shows the manner of making contact with an ordinary conductor. The bare or bared conducting wires 45 are placed upon 55 the contact plates 2 and 3, after which clamping plate 5 is by means of nut 6 forced down, until a good contact has been established. The obtuse-angled form of recesses on elevations 16 prevents the conductors 60 from falling out.

Fig. 7 illustrates the method of making electrical connection with an insulated cable wire, which is likewise produced by simple mechanical pressure. In this case I employ a metal piece 36 adapted to that purpose and 70 shown in Fig. 14 in perspective. This metal piece is provided with a sharp point 37 and both its ends are turned down. Metal piece 36 is pressed forcibly into the cable wire 39, Fig. 7 in such a manner that point 37 establishes 75 electrical contact with the cable wire. After this manipulation contact with the lamp is effected by placing contact plates 2 and 3 into metal pieces 36, the down-turned ends thereof preventing a sideward displacement. After this operation clamping plate 5 is forced down by means of nut 6, till a good contact is established.

Fig. 8 shows another method of making contact with an insulated cable wire; in 85 which I employ however instead of metal piece 36 a sharp metallic pointed device 40, firmly secured to contact plates 2 and 3. The pointed device 40, a perspective view of which is shown in Fig. 15, may be either of 90 conical or of pyramidal form, and is firmly secured to contact plates 2 and 3 either by means of a screw thread 41 or as illustrated in Fig. 8 right side by means of a rivet 42. The electrical contact is established in the 95 same manner as described before, that is, by simple mechanical pressure.

I am aware that prior to my invention lamp sockets with pointed devices to establish electrical contact have been made. So 100 far as I know in all these inventions a screw driver or such similar article is required to make contact and the pointed devices are movable in the socket, while in my socket the contact is effected by a single manipulation, 105 namely the forcing down of the clamping plate against the insulating support, thereby pressing the fixed metallic points into the conductor wires, avoiding the use of a screw driver and effecting a considerable saving of 110 time and labor in the installation of the appliance.

What I do claim and desire to secure by Letters Patent, is—

1. In an electric lamp-socket, the combination of a support of insulating material having an interior thread to receive the base of an electric lamp, perforations extending through the base of the support, contact-plates secured therein and bent over the base 115 of the support at their inner and outer ends, a clamping-plate of insulating material provided with raised portions, and means for holding said clamping-plate on the base of the support for supporting the conductors in 120 contact with the contact-plates.

2. In an electric lamp-socket, the combination of a support of insulating material having an interior screw-thread adapted to receive the base of an electric lamp, said sup- 125

port being provided in its base with perforations, contact-plates secured into said perforations and provided with bent-over contact-surfaces at their inner and outer ends, a 5 raised portion at the outer surface of the base for separating the outer ends of the contact-plates from each other, a clamping-plate of insulating material provided with raised portions, and means for clamping the conducting-wires interposed between the contact-plates and the raised portions of the clamping-plate firmly in position on the support.

3. In an electric lamp-socket, the combination of a support of insulating material having an interior thread adapted to receive the base of an electric lamp and having a grooved channel at one side of the thread, 15 perforations and a central hole in said base, contact-plates secured in the perforations in 20 the base, one of the contact-plates being seated in said side-groove of the interior thread, an elevation on the base of the support for separating the outer ends of the contact-plates, a screw-post seated in the central 25 hole of the base, a clamping-plate of insulating material provided with raised portions for holding the conducting-wires, and a

screw-nut applied to the end of the screw-post for holding the clamping-plate in position on the base of the support. 30

4. In an electric lamp-socket, the combination of a support of insulating material having an interior screw-thread adapted to receive the base of an electric lamp, the base of the support being provided with perforations and a central shouldered hole, contact-plates inserted in the perforations of the base, a raised portion on the outer surface of the base for separating the contact-plates, a screw-post secured in said shouldered hole, a 35 clamping-plate of insulating material provided with a central opening for the screw-post and raised portions obtusely recessed at their faces, and a screw-nut for holding the conductors and the clamping-plate firmly on 40 the base of the support. 45

In testimony whereof, I have signed my name to this specification in the presence of two subscribing witnesses.

JOSEPH AMON.
